CLAIM

The ornamental design for a portable blender, as shown and described.

DESCRIPTION

FIG. 1 is a first perspective view of a portable blender showing my new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof; and,

FIG. 9 is a perspective view of the portable blender in an open state of use.

The broken lines shown in the drawings depict portions of the portable blender that form no part of the claimed design.

1 Claim, 9 Drawing Sheets
